(57) **CLAIM**

The ornamental design for dental model base having two rows of pins, as shown and described.

DESCRIPTION

FIG. 1 is a perspective view of the present invention.

FIG. 2 is a top plan view thereof.

FIG. 3 is a bottom plan view thereof.

FIG. 4 is a front elevation view thereof.

FIG. 5 is a rear elevation view thereof; and, FIG. 6 is a side view thereof.

UNITED STATES PATENT AND TRADEMARK OFFICE
CERTIFICATE OF CORRECTION

PATENT NO. : Des. 464,733 S
DATED : October 22, 2002
INVENTOR(S) : Huffman

Page 1 of 1

It is certified that error appears in the above-identified patent and that said Letters Patent is hereby corrected as shown below:

Title page.

Item [75], Inventor, address should read -- Oro Valley, AZ (US) -- rather than
"P.O. Box 1328, Sapulpa, OK (US) 74066"

Item [73], Assignee, please delete all assignee data. The patent was not assigned.

Signed and Sealed this

Fifth Day of August, 2003

JAMES E. ROGAN
Director of the United States Patent and Trademark Office
